NEW EAGLE HOT AIR. NO 3

Des.

536

S. S. Jewett & Francis A. Root, of Buffalo, N. Y.
Letters Patent No 536. Dated Dec 21. 1852.

The schedule referred to in these Letters Patent, and making part of the same.

To all whom it may concern:

Be it known, That we, S. S. Jewett & F. A. Root, of Buffalo in the County of Erie and State of New York, have invented or produced a new and ornamental design for Cooking Stoves, of which the following is a full, clear and exact description, reference being had to the accompanying drawings, which form part of this specification, and which represent the configuration of the device embellishing the plates and doors of the stove.

The general figure of the stove is that of an oblong approximating a square, and its construction involves an elevated fire-box, the front plate (A) of which has the inscription "New Eagle Stove Co. No. 3" on or along it, and over and above fire doors B.B. These doors have the same ornamental configuration as that of the door A on the side plate C, differing only in proportions from the said door. Both side plates of the stove are similar in every respect, each one (C) having within a moulded border, an ornamental panel E, and doors F.G, the embellishments of which consist of somewhat similar devices, varying mainly in proportions and the figures formed by their outer terminations: these devices consist of an annular moulding (a) projecting from within the apex, as it were of a hollow cone or dished surface made up of straight, tapering, convex fillets (b) converging towards the apex of the cone and bevelled at their outer ends, so as to give the panel, a scalloped outline, the said fillets having tufted or beaded mouldings (c) for their borders. The annular central moulding (a) of the larger door F, differs slightly from the annular mouldings (a) of the other doors, and the panel, is assumed that it had a central projecting pyramidal point, otherwise

Des. 536

the configuration of the several annular mouldings is the same, consisting of an outer ovolu ring, joined to a concentric ring or head by a circular cavetto. The fillets (b) of the door E, converging from the upper corner of the said door, terminate in a curved outline or boundary, in conformity with the rounded upper corners of the door. The outer termination of these fillets (b) in the other several doors form the outlines to panels of parallelogramic contour corresponding with the oblong shapes of the said doors; and the same converging fillets on the panel B terminate in a square figure or outline.

The panel E, which is in shape a trapezoid, projects outwards from the side plate and (protruding with it) the top front corner of the side plate similarly projects.

Having thus described our ornamental design for cooking stoves, what we claim as new therein, and desire to secure by letters patent is - the configuration and arrangement of the several devices, ornamenting the panels and doors, the same consisting of annular mouldings, surrounding the apex of a dished or hollow cone surface formed of converging fillets whose outer ends form a scalloped outline or border for the panel, as represented & described.

In testimony whereof we have hereunto subscribed our names
